COLD FLOW PREVENTING PACKING STRUCTURES

John R. Baker, Pasadena, Calif., assignor to Baker Oil Tools, Inc., Los Angeles, Calif., a corporation of California

Application August 26, 1957, Serial No. 680,102

14 Claims. (Cl. 166—204)

The present invention relates to subsurface well tools, and more particularly to packing devices adapted to be disposed in well bores for effecting seals against casings, liners, and the like, previously located within the well bores.

Packing elements employed in well bores are ordinarily made of rubber or rubber-like materials, or similar pliant, elastic materials. The packing element usually bears against an abutment having a substantial clearance with the wall of the surrounding well casing, liner, or the like. Upon being subjected to substantial forces, the packing element tends to cold flow into the clearance space around the adjacent abutment. Such cold flowing action is most pronounced in well bores having relatively high temperatures and pressures. In some instances, the cold flowing is of such an extent as to result in the forcing of a large portion, if not all, of the packing material into the clearance space, resulting in failure of the packing element.

It is an object of the present invention to provide an improved packing structure embodying a pliant, elastic packing element which is prevented from cold flowing into the clearance space around an adjacent abutment, despite the fact that the packing element might be subjected to high pressures, high temperatures, or both.

Another object of the invention is to provide a packing structure, which includes a pliant, elastic packing element and a cold flow preventing device for precluding shifting of the packing material around an adjacent abutment, the packing element being instrumental in shifting the cold flow preventing device to its operative position, there being no spaces in the preventing device through which the packing material can be forced.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a combined longitudinal section and side elevational view of the well packer disposed in a well casing, with the packer parts in their initial, retracted positions;

Fig. 2 is a view similar to Fig. 1, illustrating the well packer after it has been anchored in packed-off condition in the well casing;

Fig. 3 is a plan view of the flow preventing device, with parts broken away;

Fig. 4 is an enlarged fragmentary longitudinal section through the flow preventing device.

The packing structure 10 is illustrated by way of example in the drawings as forming part of a well packer A to be anchored in packed-off condition within a well

2

casing B, or the like. The well packer itself is adapted to be lowered in the well casing to the desired setting point by means of a tubular string C, such as a string of tubing, with the exterior parts of the well packer disposed initially in a retracted position to permit freedom of passage through the casing to the desired setting point.

The packer includes a main body 11 which carries a set of upper segmental slips 12 adapted to be moved into engagement with the casing B by an upper frusto-conical expander 13 retained initially in retracted position by one or more shear screws 14 securing it to the main body. The upper slips are also retained initially in retracted and ineffective position by shear screws 15, 16 securing them to the expander and the main body.

15 A lower set of segmental slips 17 is initially held in retracted position, by being attached to the main body 11 through the medium of shear screws 18 and to a lower frusto-conical expander 19 through additional shear screws 20, this latter expander being held initially in 20 ineffective position by suitable frangible connections in the form of shear screws 21 threaded into the body 11.

The packing structure 10 includes a packing sleeve 22 of synthetic or natural rubber positioned between the expanders 13, 19, being retained initially free from contact with the casing wall, but being capable of 25 fore-shortening and expansion into engagement therewith and the main body 11 of the packer.

A valve assembly housing 23 is threadedly secured to the lower end of the main packer body 11, carrying there within a tripping ball seat 24 initially secured thereto by a shear screw 25. This seat has an upstanding arm 26 for holding a buoyant back pressure ball 27 in ineffective position against the interior of the housing, to prevent its seating against a valve seat 28 provided at the lower end of the main body. Removal of this arm 26 through a proper operation will permit the ball 27 to be positioned against its cooperable valve seat 28 whenever reverse flow through the body 11 tends to occur.

The well packer A is run in the casing B to the desired setting point and circulation established therethrough to remove any undesired foreign matter in the well casing. Thereafter, a tripping ball 29 is lowered or pumped down through the tubing string C into seating engagement with the tripping ball seat 24, permitting increase of the pressure of the fluid within the packer body 11, and its passage through ports 30 opening through the body into the interior of the packing sleeve 22. This fluid under pressure will shear the screws 14 and shift the upper expander 13 upwardly along the body 11 to disrupt the various shear screws 15, 16 and shift the upper slips 12 against an upper setting ring 31, secured to the body, and outwardly into gripping engagement with the well casing B. After the upper slips 12 have been set in the manner described, the pressure of the fluid is increased to shear the screw 25 holding the tripping ball seat 24 to the valve housing 23, the fluid ejecting the seat 24 together with its upstanding arm 26 from the valve housing and allowing the back pressure ball 27 to engage the seat 28 whenever reverse flow of fluid tends to occur.

An upwardly directed pull or strain is then taken on the tubular string C and the main body 11 of the packer, which will foreshorten the packing sleeve 22 by moving the lower expander 19 toward the upper expander 13 and expand the packing sleeve against the casing wall and the exterior of the main body 11. A continuation of the upwardly directed strain on the tubular string C and body B will shear the screws 18, 20, 21 holding the lower slips 17 to the body and expander 19, and the expander 19 to the body 11, causing an abutment 32 at the lower end of the body 11 to engage the slips 17 and move them longitudinally along the outer face

of the lower expander 19 and radially into engagement with the casing B. An increase in this upward strain will further move the lower slips 17 and expander 19 toward the upper slips 12 and expander 13, further compressing the packing sleeve 22 between the casing wall B and exterior of the body 11, to effect a leakproof seal therebetween.

The parts are retained in the set position illustrated in Fig. 2 by preventing downward movement of the body 11 relative to the part surrounding it. This can be accomplished by providing a split, contractile ratchet ring 33 in an internal groove 34 in the upper expander 13, this ratchet ring being adapted to engage circumferential ratchet teeth 35 formed in the periphery of the packer body. The teeth 35 on the body face in a downward direction whereas the ratchet ring faces in an upward direction, so as to permit the body 11 to move upwardly relative to the upper expander 13, but precluding downward movement of the body with respect thereto.

The upper and lower expanders 13, 19 form abutments at the upper and lower ends respectively of the pliant, elastic packing element or sleeve 22. As disclosed, the end portions 22a of the packing sleeve may be reduced in diameter to fit in companion recesses 40 in the upper and lower abutments or expanders. To assure the passage of the well packer A down through the fluid in the well casing B, a substantial annular clearance 41 is provided between the abutments or expanders 13, 19 and the wall of the surrounding well casing. Such annular clearance space is a source through which the rubber or rubber-like packing material 22 can be extruded, following the setting of the packer and expansion of the packing sleeve 22 into sealing engagement between the body 11 of the tool and the wall of the well casing B. Such extrusion can occur more readily when the well packer is subjected to high temperatures or high pressures, and will occur most readily when the packing sleeve is subjected to a combination of high pressures and high temperatures.

The present invention prevents the cold flowing or extrusion of the packing material through the clearance space 41 existing between an abutment 13 or 19 and the wall of the surrounding well casing B. To accomplish this purpose, an extrusion preventing device 42 is provided at each end portion of the packing sleeve 22 and the adjacent abutment or expander. As specifically disclosed, the end 43 of the upper abutment 13 is tapered in an upward and outward direction, the confronting portion 44 of the packing sleeve 22 also being tapered, but in a downward and outward direction, thereby defining a generally triangularly-shaped groove 45 between the tapered surfaces 43, 44 which extends circumferentially around the abutment and the confronting portion of the packing sleeve. An outer metallic ring 46 is positioned in the groove 45, having an inner tapered surface 47 engageable and companion to the tapered surface 43 on the abutment. This ring is also of generally triangular cross-section. In fact, it may be of generally right triangular cross-section, with its outer surface 48 generally cylindrical, and with its lower surface 49 relatively flat and substantially normal to the axis of the well packer.

An inner ring 50, reversely arranged to the outer ring 46, is also disposed in the lower portion of the groove 45, having a tapered inner surface 51 engageable with and companion to the tapered surface 44 on the packing sleeve 22. This inner ring 50 is also of generally triangular cross-section. As specifically disclosed, it is of generally right triangular cross-section, with its outer surface 52 generally cylindrical and forming a continuation of the outer surface 48 of the other ring 46. Its upper surface 53 may also be normal to the axis of the well packer and abuts the lower surface 49 of the outer ring 46.

The inner and outer rings 50, 46 substantially fill the triangular groove 45 defined by the tapered surfaces 43, 44 on the upper abutment 13 and the confronting face of the packing sleeve 22. These rings are each split and normally tend to remain in a retracted position, such as disclosed in Fig. 1. However, the rings 46, 50 are expandable outwardly to bring their cylindrical surfaces 48, 52 into engagement with the cylindrical wall of the well casing B. The splits 60, 61 of the rings are staggered with respect to each other. In fact, they are preferably arranged approximately 180 degrees from one another.

To assure the same extent of outward expansion of the rings, they are keyed to one another, for circumferential slidable movement with respect to one another, but with relative radial movement being prevented, by an arcuate key and slot arrangement. As specifically disclosed, one of the rings 50 has a circumferential rib 62 projecting upwardly from its upper face 53, this rib fitting within a companion circumferential groove 63 in the lower portion of the outer ring 46. By virtue of the key and keyway or slot arrangement 62, 63 described, the rings 46, 50 will expand outwardly to the same extent, as described hereinbelow. However, the interconnection 62, 63 between the rings will not prevent such expansion from occurring. By placing the splits 60, 61, 180 degrees from one another the rings together exert a uniform force around their circumference resisting their outward expansion.

If desired, a similar flow preventing device 42a may be provided between the lower expander or lower abutment 19 and the confronting portion 44a of the packing sleeve 22.

In the operation of each flow preventing device, when the packer body 11 is moved in an upward direction, after the upper set of slips 12 has been expanded against the well casing B, in the manner described above, the lower abutment or expander 19 is moved by the body toward the upper abutment or expander 13, foreshortening the packing sleeve 22 and causing it to shift outwardly against the wall of the well casing. During the foreshortening of the packing sleeve between the abutments 13, 19 and its outward expansion, the tapered surface 44 on the packing sleeve bears against the tapered surface 51 on the inner ring 50 and urges the latter in an outward direction toward the wall of the well casing. The upward force imparted to the packing sleeve 22 is transmitted through the inner ring 50 to the outer ring 46, the tapered surface 47 of the latter bearing upon the companion tapered surface 43 on the upper expander or abutment 13, which also effects an outward shifting of the outer ring 46 toward the well casing B. The combination of the tapered surfaces 44, 43 on the packing sleeve 22 and on the abutment 13 shifts the outer rings 46, 50 outwardly, such rings moving outwardly to the same extent in view of their arcuate or circumferential key or rib and groove or slot interconnection 62, 63, until both rings are brought into firm engagement with the wall of the well casing. When so engaged, the outer ring 46 still has substantial engagement with the abutment 13. Each ring will contact the wall of the well casing for substantially 360 degrees, except for the arcuate extent of split 60 or 61 in each ring. However, since the slots or splits 60, 61 are staggered with respect to one another, the inner and outer rings 46, 50 of each flow preventing device will engage the wall of the well casing B and bridge the clearance space 41 between the abutment 13 and the well casing, no gaps or spaces existing through the flow preventing device 42 into and through which the packing material can flow (Fig. 2).

If the lower flow preventing device 42a is used it will also be expanded outwardly as a result of the longitudinal forces imposed upon the packing sleeve 22, the inclined surfaces coacting with one another to effect a shifting of both rings 46, 50 of the lower device outwardly until

their cylindrical surfaces 48, 52 engage the wall of the well casing B.

The rings 46, 50 of each extrusion preventing device 42, 42a may be made of a suitable material which will withstand comparatively high pressures and temperatures without deforming their cross-section. For example, the rings may be made of ductile iron. When made of such material, the rings will not deform significantly and will always bridge the clearance space 41 between each abutment and the wall of the well casing, resisting extrusion into the clearance space.

The inventor claims:

1. A packing structure, including a non-metallic packing member adapted to engage a companion wall, an abutment adjacent said member and having a tapered expander surface, a first split functionally integral ring engaging said packing member, a second split functionally integral ring engaging said tapered surface and said first ring and circumferentially slidable on said first ring, and means securing said rings to one another for joint movement toward engagement with the companion wall in response to movement of the packing member into engagement with the companion wall.

2. A packing structure, including a non-metallic packing member adapted to engage a companion wall and having a first tapered expander surface, an abutment adjacent said member and having a second tapered expander surface opposite said first expander surface, a first split ring engaging said first tapered surface, a second split ring engaging said second tapered surface and said first ring and circumferentially slidable on said first ring, and means securing said rings to one another for joint movement toward engagement with the companion wall in response to movement of the packing member into engagement with the companion wall.

3. A packing structure, including a non-metallic packing member adapted to engage a companion wall and having a first tapered expander surface, an abutment adjacent said member, a first split ring engaging said tapered expander surface, a second split ring engaging said abutment and said first ring and circumferentially slidable on said first ring, and means securing said rings to one another for joint movement toward engagement with the companion wall in response to movement of the packing member into engagement with the companion wall.

4. A packing structure, including a non-metallic packing member adapted to engage a companion wall, an abutment adjacent said member, a first split functionally integral ring engaging said packing member, a second split functionally integral ring engaging said abutment and said first ring and circumferentially slidable on said first ring, and means securing said rings to one another for joint movement toward engagement with the companion wall in response to movement of the packing member into engagement with the companion wall.

5. A packing structure, including a non-metallic packing member adapted to engage a companion wall, an abutment adjacent said member, a first split ring engaging said packing member, a second split ring engaging said abutment and said first ring and circumferentially slidable on said first ring, one of said rings having an arcuate groove therein, and an arcuate rib on the other of said rings disposed in said groove to cause both of said rings to move jointly toward engagement with the companion wall in response to movement of the packing member into engagement with the companion wall.

6. A packing structure, including a non-metallic packing member adapted to engage a companion wall and having a first tapered expander surface, an abutment adjacent said member and having a second tapered expander surface opposite said first expander surface, a first split ring engaging said first tapered surface, a second split ring engaging said second tapered surface and said first ring and circumferentially slidable on said first ring,

one of said rings having an arcuate groove therein, the other of said rings having an arcuate rib disposed in said groove to cause said rings to move jointly toward engagement with the companion wall in response to movement to the packing member into engagement with the companion wall.

7. A packing structure, including a non-metallic packing member adapted to engage a companion surrounding wall and having a first tapered expander surface, an abutment adjacent said member and having a second tapered expander surface opposite said first expander surface, a first split ring engaging said first surface and having a generally cylindrical outer surface, a second split ring engaging said second surface and having a generally cylindrical outer surface, and means securing said rings to one another for circumferentially shiftable relation to each other and for joint outward expansion into engagement with the surrounding wall in response to movement of the packing member toward said abutment and into engagement with the companion wall.

8. A packing structure, including a non-metallic packing member adapted to engage a companion surrounding wall and having a first tapered expander surface, an abutment adjacent said member and having a second tapered expander surface opposite said first expander surface, a first split ring engaging said first surface and having a generally cylindrical outer surface, a second split ring engaging said second surface and having a generally cylindrical outer surface and circumferentially slidable on said first ring, one of said rings having an arcuate groove therein, and an arcuate rib on the other of said rings disposed in said groove to cause said rings to expand jointly into engagement with the surrounding wall in response to movement of the packing member toward said abutment and into engagement with the surrounding wall.

9. A packing structure, including a non-metallic packing member adapted to engage a companion surrounding wall and having a first tapered expander surface, an abutment adjacent said member and having a second tapered expander surface opposite said first expander surface, a first split ring of generally triangular cross-section having a tapered surface engaging said first surface and also having a generally cylindrical outer surface, a second split ring of generally triangular cross-section having a tapered surface engaging said second surface and also having a generally cylindrical outer surface, said rings being circumferentially shiftable relative to each other and having opposed surfaces substantially normal to said outer surfaces and engaging one another, one of said rings having an arcuate groove extending in an axial direction inwardly from its normal surface, and the other of said rings having an arcuate rib projecting axially from its normal surface and disposed in said arcuate groove to cause said rings to move jointly outwardly into engagement with the surrounding wall in response to movement of the packing member towards said abutment and into engagement with the surrounding wall.

10. A packing structure, including a non-metallic packing member adapted to engage a companion wall, an abutment adjacent said member and having a tapered expander surface, a first split functionally integral ductile ring engaging said packing member, a second split functionally integral ductile ring engaging said tapered surface and said first ring and circumferentially slidable on said first ring, and means securing said rings to one another for joint movement toward engagement with the companion wall in response to movement of the packing member into engagement with the companion wall.

11. A packing structure, including a non-metallic packing member adapted to engage a companion wall, an abutment adjacent said member, a first split functionally integral ductile ring engaging said packing member, a second split functionally integral ductile ring engaging said abutment and said first ring and circumferentially slidable on said first ring, one of said rings having an arcuate groove therein, and an arcuate rib on the other of said

rings disposed in said groove to cause both of said rings to move jointly toward engagement with the companion wall in response to movement of the packing member into engagement with the companion wall.

12. A packing structure, including a non-metallic packing member adapted to engage a companion surrounding wall and having a first tapered expander surface, an abutment adjacent said member and having a second tapered expander surface opposite said first expander surface, a first split functionally integral ductile ring engaging said first surface and having a generally cylindrical outer surface, a second split functionally integral ductile ring engaging said second surface and having a generally cylindrical outer surface, and means securing said rings to one another for circumferential shifting relative to each other and for joint outward expansion into engagement with the surrounding wall in response to movement of the packing member toward said abutment and into engagement with the companion wall.

13. A packing structure, including a non-metallic packing member adapted to engage a companion wall, an abutment adjacent said member, a first split functionally integral ductile ring engaging said packing member, a second split functionally integral ductile ring engaging said abutment and said first ring and circumferentially slideable on said first ring, and means securing said rings to one another for joint movement toward engagement with the companion wall in response to movement of the packing member into engagement with the packing wall.

14. A packing structure, including a non-metallic pack-

ing member adapted to engage a companion surrounding wall and having a first tapered expander surface, an abutment adjacent said member and having a second tapered expander surface opposite said first expander surface, a first split functionally integral ductile ring, a generally triangular cross-section having a tapered surface engaging said first surface and also having a generally cylindrical outer surface, a second split functionally integral ductile ring and generally triangular cross section having a tapered surface engaging said second surface and also having a generally cylindrical outer surface, said rings being circumferentially shiftable relative to each other and having opposed surfaces substantially normal to said outer surfaces and engaging one another, one of said rings having an arcuate groove extending in an axial direction inwardly from its normal surface, and the other of said rings having an arcuate rib projecting axially from its normal surface and disposed in said arcuate groove to cause said rings to move jointly outwardly into engagement with the surrounding wall in response to movement of the packing member toward said abutment and into engagement with the surrounding wall.
